UNITED STATES PATENT OFFICE.

JOHN A. BENNAN, OF CHICAGO, ILLINOIS.

ELECTRICAL-SWITCH MOUNTING.

1,167,880.

Specification of Letters Patent.

Patented Jan. 11, 1916.

Application filed November 9, 1914. Serial No. 870,954.

To all whom it may concern:

Be it known that I, JOHN A. BENNAN, a citizen of the United States, and a resident of Chicago, in the county of Cook and State of Illinois, have invented certain new and useful Improvements in Electrical-Switch Mountings; and I do hereby declare that the following is a full, clear, and exact description thereof, reference being had to the accompanying drawings, and to the characters of reference marked thereon, which form a part of this specification.

This invention relates to a novel electric switch and mounting therefor, which mounting is adapted to constitute a unitary part of a structure in connection with which the switch is to be used, or which may constitute an independent switch adapted for general use.

20 Among the objects of the invention is to provide, what may be termed, an "indestructible" switch which is capable of severe usage without liability of breakage of the switch supporting base or switch elements 25 and consequent grounding of the switch terminals.

A further object of the invention is to provide an exceedingly simple device of this character in which the parts are held in reliable fixed relation to each other, and which may be made and installed at small cost.

The invention consists in the matters hereinafter set forth and more particularly pointed out in the appended claims.

35 I have herein shown my invention as applied to a sheet metal battery box adapted, among other things, to contain one or more battery cells to constitute part of an ignition system for a gas engine, and have also indicated the manner in which the switch may 40 be made an independent device for general use.

In the drawings, Figure 1 is a perspective view of a battery box provided with a 45 switch embodying my invention. Fig. 2 is an enlarged fragmentary face view of the switch proper. Fig. 3 is a section on the line 3-3 of Fig. 2. Fig. 4 is a section on the line 4-4 of Fig. 2. Fig. 5 is a partial outer face view of the switch base. Fig. 6 is a perspective view of a binding post 50 constituting an element of the switch. Fig. 7 is a transverse section of a modification of the switch. Fig. 8 is a plan view of a blank of a form to constitute one of the switch terminal clips.

In Figs. 1 to 5, inclusive, of the drawings, my improved switch is shown as mounted on and constituting a unitary part of a battery box 9 which may be made of any suitable dimension and shape. Said box is made of sheet metal, and when the switch is applied as a unitary part of the box the base 10 of the switch is made an integral part of the box, it being struck or stamped outwardly from one of the walls thereof by a suitable swaging die. Said base is hollow and comprises an outer wall 11 and a surrounding flange or wall 12.

The switch shown in Figs. 1, 2 and 3 is 70 a two-throw switch, but it is obvious that my improvements are equally well adapted to a single-throw switch, or to other types of switches. Said switch embodies, as more clearly shown in Figs. 1 and 3, a switch 75 blade 16 that is pivoted to the outer wall 11 of the base, and terminal clips 17, 17 mounted, when embodied in a double-throw switch, one at each side of the pivot 18 of the blade 16. As shown, each of the clips 17 is made 80 of a single piece of metal, the blank 19 of which is shown in Fig. 8. Said blank comprises twin portions which are adapted to be folded one upon the other about the neck portion 20 as a hinge to provide separated 85 lips 21, 21, between which the switch blade 16 is adapted to be engaged. Each clip is attached to the base 10 by means of a bolt 22, best shown in Fig. 6. Said bolts 22 may also constitute binding posts or terminals 90 for connection with the circuit wires. Each bolt comprises a head 23, a squared or other irregularly shaped shank 24 and a screw-threaded portion 25, the latter adapted to receive a nut 26.

95 As shown in said Figs. 1, 3 and 4, the bolts or binding posts 22 are arranged for, what is termed a back connection, or with the screw-threaded ends and nuts inside the base and the head 23 of the bolt outside 100 of and overlying the exterior faces of the terminal clips 17. Said bolts extend through an insulating sheet 26' made of any suitable stiff fibrous material that lies against the inner side of the flat wall 11 of the base, through openings 27 in said wall 11, through insulating members 28 between said wall and the terminal clips and through openings 29 of the members of the clip. The clips are thus clamped upon the base by means 105 of the clamping nuts 26 screw-threaded to the inner ends of the bolts, and the circuit 110

wire may be attached to the inner ends of the bolts or binding posts in any suitable or preferred manner. The said insulating member 26' is made of such dimensions as 5 to closely fit at its edges the flanged wall 12 of the switch base so as to be thereby held fixedly in place. It is provided with squared or other non-circular openings 30 through which the binding posts extend, the 10 squared or other non-circular portions 24 of the bolts fitting closely in the like-shape openings of the sheet 26' so as to thereby prevent rotation of the binding posts bolts.

The insulating members 28 which lie between the base and the clips 17 and the said clips are also provided with squared openings to receive the squared portion of the shanks of the binding post bolts, whereby 15 said parts are held fixedly in place relatively to the base. That is to say, the insulating member 26', by reason of its interfitting engagement with the base, holds the binding post bolts from rotation and the interlocking engagement of the bolts with the insulating members 28 and clips 17 hold the latter from turning on said bolts. The 20 openings 27 in the wall 11 of the base is made substantially larger than the portion of the binding post bolts which extend there-through, so as to thereby suitably insulate the bolts from the metal of the base.

The switch blade is pivoted to the base through the medium of the bolt 18 which constitutes a combined pivot bolt and binding post. It extends inwardly through said switch blade, the wall 11 of the base and the insulating member 26', and is held in place by a nut 36 screw-threaded to the bolt 18. An insulating washer 37 is interposed between 25 the pivoted end of the switch blade and the base, and preferably other washers are arranged on the bolt 18 at the sides of the switch blade so as to thereby provide a suitable pivotal engagement of the switch blade with said bolt.

The construction shown in Fig. 7 is adapted as an individual switch to be attached to a suitable support for various uses. In this construction the base 40 of the switch 30 comprises a flat outer wall 41 and a surrounding flange wall 42, preferably provided with a foot flange 43 to bear against the part to which the switch body is attached to afford a suitably wide bearing therefor. 35 The circuit connections will preferably be front connections so that the binding post bolts are arranged with their heads inside the wall 41 and with their screw-threaded ends extending outwardly to engage the 40 clamping nuts by which the circuit wires may be attached to the bolt. In other respects, the construction of the switch is essentially the same as that just described, and like parts are designated by the same reference numerals.

The construction described provides a very strong, durable and non-breakable body which carries the elements of the switch, and also provides a reliable insulation between said switch elements. Moreover, said switch elements are maintained in fixed relation to each other and to the base by a very simple construction.

In the adaptation of the switch structure as a unitary part of a box to contain a set 75 of batteries, a further advantage is found in that no additional metal is required to furnish the switch base, and also that the work of assembling the switch on the battery box, and separately applied attaching 80 means, as bolts or screws, is thereby rendered unnecessary.

Heretofore, it has been a common practice in manufacturing switches of the general character described to make the base of porcelain, rubber compound or the like. Such material is relatively fragile and when subjected to external bruises is liable to breakage, thus necessitating the replacement thereof and often occasioning a short circuit between 90 the switch elements carried by the base. A rubber or like compound is further objectionable by reason of its comparatively low-fusing point, which often leads to a heat break down when used in high temperatures. 95

The construction herein described is of such nature as may be subjected to severe treatment in the way of external bruises, concussions or the like without liability of the parts being broken down, or short circuited 100 between the switch terminals, and is capable of use in heated locations, as in and about a gas engine, without danger of overheating.

A further advantage of the construction 105 described is the economy by which it may be produced, it being obvious that the several sheet metal parts and insulating members of the device may be rapidly and cheaply stamped or cut from their proper 110 materials and readily assembled. Another advantage of the construction described is that the binding posts serve to reliably connect the elements of the switch and the insulating elements to the base so that there- 115 by the parts are held in fixed relation to each other.

I claim as my invention:

1. An electrical switch mounting comprising a sheet metal base formed with a non-circular recess on the interior thereof, a sheet of insulating material fitted in said non-circular recess, a second sheet of insulating material in contact with the exterior of said base, openings through said base, non-circular openings through said insulating sheets of less size than the openings through said base, combined clamping bolts and binding posts extending through said openings and shaped to fit the non-circular 125 130 135

openings in said insulating sheets, electrical contact members interlocked with said binding posts exterior of said base, and means for connecting and disconnecting said electrical contact members.

2. In combination a sheet metal casing, a plate forming a closure for one side of said casing and having an integral extension struck outwardly therefrom and forming a switch base having a non-circular recess on the interior thereof, a plurality of openings through said switch base, a sheet of insulating material fitted to the interior of said switch base and having openings therein registering with the openings in said base and smaller than said openings, combined clamping bolts and binding posts interlocked with the openings in said insulating sheet and extending through the openings in said base and having an air space between them and the walls of said openings, an electrical contact member secured to one of said binding posts and insulated from said base, and an electrical switch pivoted to another of said binding posts insulated from said base and adapted to be swung into and out of contact with said electrical contact member.

3. An electrical switch comprising a flanged sheet metal base, an insulating sheet member applied to the inner side of the base and held in fixed relation thereto by engagement with the base flange, an insulating member between said clip and base, registering openings extending through said insulated members and base, the openings in said base being larger than the openings in said insulating members, binding posts having non-rotative interlocking connection with the openings in said insulating members and passing through the openings in said base, electrical contact members secured to said binding posts exterior to said base, and an electrical switch secured to one

of said binding posts and adapted to connect and disconnect said electrical contact members.

4. In a device of the character described, a box adapted to contain batteries or other electrical apparatus and having a sheet metal closure for one side thereof, a projection struck outwardly from said closure and forming a hollow base of non-circular shape, a sheet of insulating material placed within said base and fitted to the interior thereof, openings through said base, non-circular openings through said insulating sheet of less size than the openings through said base, binding posts passing through said non-circular openings and fitting closely therein, electrical contact members secured to said base by said binding posts exterior to said base, and a pivoted switch adapted to make and break electrical connection between said contact members.

5. In combination, a container having sheet metal side walls and a bottom connected together to form a box for holding electric batteries, a portion of one of said side walls being struck outwardly to form a hollow switch base of non-circular formation, a sheet of insulating material fitted to the interior of said switch base, and a plurality of electrical contact members non-rotatably interlocked with said insulating sheet and passing through openings in said base without contacting therewith, whereby said electrical contact members are held from movement by said insulating material relative to one another and relative to said material.

In testimony, that I claim the foregoing as my invention I affix my signature in the presence of two witnesses, this 23rd day of October, A. D. 1914.

JOHN A. BENNAN.
